UNITED STATES PATENT OFFICE.

HENRY SCHLOERB, OF NEW YORK, N. Y.

DESIGN FOR A TOY BANK.

SPECIFICATION forming part of Design No. 32,972, dated July 17, 1900.

Application filed February 27, 1900. Serial No. 6,758. Term of patent 7 years.

To all whom it may concern:

Be it known that I, HENRY SCHLOERB, a citizen of the United States, residing at No. 500 West One Hundred and Fifty-ninth street, 5 New York, borough of Manhattan, county and State of New York, have invented and produced a new and original Design for Toy Banks, of which the following is a specification, reference being had to the accompanying drawings, forming part thereof.

As shown in the drawings, the leading or material features of my design, which is a 15 representation of a grotesque human face, consist of the prominent cheek portions a a, the protruding lips b b of the open mouth, and the ample beard c.

Having described my invention, what I 20 claim as new, and desire to secure by Letters Patent, is—

The design for a toy bank as herein shown and described.

HENRY SCHLOERB.
